UNITED STATES PATENT OFFICE.

ARTHUR TREVOR DAWSON AND GEORGE THOMAS BUCKHAM, OF WESTMINSTER,
LONDON, ENGLAND, ASSIGNEES TO VICKERS LIMITED, OF WESTMINSTER,
ENGLAND.

ORDNANCE.

1,318,055.

Specification of Letters Patent.

Patented Oct. 7, 1919.

Original application filed July 7, 1917, Serial No. 179,268. Divided and this application filed June 26, 1919.
Serial No. 306,956.

To all whom it may concern:

Be it known that we, Sir ARTHUR TREVOR DAWSON, knight, and Sir GEORGE THOMAS BUCKHAM, knight, both subjects of the King of Great Britain, residing at Vickers House, Broadway, Westminster, in the county of London, England, have invented certain new and useful Improvements in or Relating to Ordnance, of which the following is 10 a specification.

This invention relates to ordnance of the kind having means whereby the gun can be depressed to a convenient angle for loading without disturbing the sights, the said 15 means comprising a pivoted member between which and the gun cradle suitable gearing (termed the elevating loading gear) is disposed and which is displaced by the elevating gear to elevate the gun and the 20 sights together; the portions of the said member that are contiguous to its pivotal axis are disposed between the gun cradle and the carriage side cheeks. The invention is particularly applicable to naval guns of 25 the casemate or upper deck type, but it may also be employed in connection with guns other than those mounted on ships.

According to the present invention the aforesaid pivoted member comprises a stirrup piece which passes under the gun cradle 30 and is loosely mounted upon the portions of the gun cradle trunnions that are situated between the cradle and the carriage side cheeks in which the said trunnions are pivoted.

In order that the said invention may be 35 clearly understood and readily carried into effect, we will describe the same more fully with reference to the accompanying drawings, in which:—

Figure 1 is a sectional side elevation of a gun mounting viewed from the left hand side showing a constructional form of our invention.

Fig. 2 is a section taken approximately on the line 2, 2 of Fig. 1, and

Fig. 3 is a view similar to Fig. 1 but as seen from the right hand side.

In these figures A is the gun and A' is 50 the gun cradle. a, a are the gun cradle trunnions and a', a' are the carriage side cheeks. B is the aforesaid pivoted member which is in the form of a stirrup piece. B'

is the elevating rack attached to this member and b' is the elevating pinion gearing with the said rack. A rack C (herein 55 termed the elevating loading rack) is connected to the member B while an operating hand wheel C' (herein termed the elevating loading hand wheel) and the gearing connecting it to the said rack are carried by the gun cradle A'. The member B need extend only a short distance in front of and behind the gun trunnions, but in order that the elevating loading hand wheel C' may be arranged near the breech end of the gun as 60 shown, the elevating loading rack C forms part of or is connected to a bar or bracket C² extending rearward from the said member B.

The stirrup piece B is loosely mounted 70 upon the portions of the gun cradle trunnions a, a that are situated between the gun cradle A' and the carriage side cheeks a', a'. The stirrup piece is formed with sight trunnions a^x, a^x which are arranged outside the 75 side members of the stirrup piece and upon which a transverse sight bracket A^x is pivoted. The sight carriers (which are mounted on vertical deflection pivots on the sight bracket A^x) may be cross-connected by a 80 transverse rod or bar. The elevating and training numbers and the elevating loading number are situated outside the side cheeks and the gear for elevating the sights for range is carried by an extension b^x on the 85 left hand side of the stirrup piece.

What we claim and desire to secure by Letters Patent of the United States is:—

1. In ordnance, the combination with the gun carriage, the sight and the gun cradle 90 having trunnions pivotally mounted in the carriage, of a stirrup piece which passes under the gun cradle and is pivotally mounted upon the portions of the gun cradle trunnions that are situated between the cradle 95 and the carriage and gearing interposed between said stirrup piece and the gun cradle for moving the gun independently of the sight.

2. In ordnance, the combination with the 100 gun carriage and the gun cradle having trunnions pivotally mounted in the carriage, of a stirrup piece which passes under the gun cradle and is pivotally mounted upon the portions of the gun cradle trunnions 105

that are situated between the cradle and the carriage, a sight bracket, a trunnion, formed on said stirrup piece, upon which said bracket is pivotally mounted and gearing interposed between said stirrup piece and the gun cradle for moving the gun independently of the sight.

3. In ordnance, the combination with the gun carriage and the gun cradle having trunnions pivotally mounted in the carriage, of a stirrup piece which passes under the gun cradle and is pivotally mounted upon

the portions of the gun cradle trunnions that are situated between the cradle and the carriage, a sight bracket extending across the cradle, trunnions, formed on said stirrup piece, upon which said bracket is pivotally mounted and gearing interposed between said stirrup piece and the gun cradle for moving the gun independently of the sight.

In testimony whereof we affix our signatures.

ARTHUR TREVOR DAWSON.
GEORGE THOMAS BUCKHAM.
